UNITED STATES PATENT OFFICE.

ALBERT G. SMALLEY, OF CHELSEA, MASSACHUSETTS.

DESIGN FOR A FRUIT-JAR.

SPECIFICATION forming part of Design No. 25,355, dated April 7, 1896.

Application filed March 4, 1896. Serial No. 581,863. Term of patent 14 years.

To all whom it may concern:

Be it known that I, ALBERT G. SMALLEY, of Chelsea, in the county of Suffolk and State of Massachusetts, have invented a new Design 5 for a Fruit-Jar, of which the following is a specification.

Referring to the accompanying drawings, Figure 1 is a top plan, Fig. 2 a bottom plan, and Fig. 3 a perspective view, of a covered 10 fruit-jar containing my design.

The views are deemed necessary to fully illustrate my new design.

The leading feature of my design consists in a squat jar squarish in cross horizontal section and rounded at all its corners with a wide peripherally-ribbed neck-band of a diameter 15 approximately equal to the distance between opposed side walls of the jar, three of the side walls of which are laterally curved, while 20 the fourth side wall is flattened.

A is the jar, of squat appearance and rounded at all its corners a.

B is the peripherally-ribbed wide neck-band, the diameter of which is approximately 25 equal to the distance between opposed side walls a' , a^2 , a^3 , and a^4 of the jar, as seen if

viewed in top plan, as in Fig. 1. Side walls a' , a^2 , and a^3 are laterally curved, and side wall a^4 is flattish.

Neck-band B laps at b inwardly over cover 30 b' , which appears as a disk, as seen in the top plan view, Fig. 1, while each of the four upper rounded corners a formed by the junction of the top and two contiguous side walls spring outwardly and downwardly from 35 the lower edge of the neck-band and between contiguous sides of the jar, the outer periphery of the neck-band falling just within the approximate square formed by the side lines of the jar, as seen also in the top plan view 40 of Fig. 1.

What I claim is—

The design for a fruit-jar herein shown and described.

In testimony whereof I have signed my 45 name to this specification, in the presence of two subscribing witnesses, on this 4th day of February, A. D. 1896.

ALBERT G. SMALLEY.

Witnesses:

EDWARD S. BEACH,
E. A. ALLEN.
